TOY FIGURINE OF LIONESS LIKENESS OR THE LIKE

Jerrold J. Krumholz, West Orange, and Herbert Happe
Van Reisgen, Westfield, N.J., assignors to Victor
Comptometer Corporation, Chicago, Ill.

Filed Jan. 22, 1973, Ser. No. 325,669

Term of patent 14 years

Int. Cl. D21—01

U.S. Cl. D34—2 R

Fig. 1

Fig. 2

Fig. 3

Fig. 4

Fig. 5

FIG. 1 is a perspective view of a toy figurine of lioness likeness embodying our new design;

FIG. 2 is a front end view thereof;

FIG. 3 is a side elevational view thereof;

FIG. 4 is a rear end view thereof; and

FIG. 5 is a bottom view thereof.

We claim:

The ornamental design for a toy figurine of lioness likeness or the like, as shown and described.
